UNITED STATES PATENT OFFICE.

HENRY E. WAITE, OF NEW YORK, N. Y.

MEDICAL BATTERY.

SPECIFICATION forming part of Letters Patent No. 395,932, dated January 8, 1889.

Application filed August 15, 1888. Serial No. 282,772. (No model.)

To all whom it may concern:

Be it known that I, HENRY E. WAITE, a citizen of the United States, residing at New York, in the county and State of New York, 5 have invented a new and useful Improvement in Medical Batteries, of which the following is a full, clear, and exact description.

My invention relates to electric batteries, and more especially to that class of batteries which 10 are specially designed to be used in electro-medical therapeutics; and the object of my invention is to produce a battery in a compact and convenient form which shall have all the apparatus necessary to the proper diagnosis of a case and the treatment thereof under the general principles of electro-medical 15 therapeutics; and my invention consists in the construction and arrangement of parts, substantially as hereinafter pointed out.

Referring to the accompanying drawings, Figure 1 is a perspective view of a device embodying my invention, and Fig. 2 is a diagrammatic arrangement of the circuits.

In the use of electricity for the treatment 25 of disease it is exceedingly desirable and important to have the electrical appliances arranged in a convenient and accessible form, whereby the practitioner may make use of electricity in various ways and can apply the 30 various kinds of currents without delay or hinderance, and while many forms of batteries have been proposed I have in my present improvement produced a battery which is comparatively simple and exceedingly convenient 35 in its arrangement and by means of which one is enabled to make use of galvanic electricity in nearly all its conditions required in the treatment of diseases.

In carrying out my invention I provide a 40 bracket or stand, which may be of any suitable material and ornamented to any amount desired, so as to form not only a useful but an ornamental office article, and in said bracket or stand I form a compartment, as A, 45 which may be closed by a suitable door, B, and in this compartment I arrange the various apparatus to be used. The battery-cells to furnish the electric current may be arranged in the base C of the bracket or stand, or may 50 be otherwise placed, as may be desired, although I have found it very convenient to have them arranged in the manner shown, as

they are readily accessible and are protected from the elements.

In the rear portion of the compartment A, 55 I mount a plate, D, of some insulating material—preferably of hard rubber or the like—and the various connections to the batteries and circuits are secured upon the rear of this plate, one arrangement of the circuits being 60 shown in Fig. 2. In the center of this plate is pivoted an arm, E, which is connected in the line-circuit, and around this central pivot are arranged a number of pins, F, to each of which is connected one of the opposite poles 65 of two battery-cells, and between these pins and pivot is arranged a circle bearing the numbers of the cells.

The construction of this device is substantially like that shown in my patent, No. 70 360,934, of April 12, 1887, and need not be particularly described herein.

Attached to a suitable binding-post, G, is a cord, g, having a plug, g', adapted to fit over any one of the pins F, and the arm E is arranged to rest upon any one of the pins, and from this it will be seen that any number of battery-cells may be included in the circuit between the pin and the operating-lever, as set forth in my patent before referred to. 80 Upon one side of this central switch is arranged a pole-changer, H, which is shown as consisting of a pivoted plug adapted to be swung to the right or left, and to bear upon two of the pins h h' h^2 h^3 on either side thereof, and to make contact therewith in a manner well understood, and more particularly pointed out hereinafter. This arm is pivoted between two brackets or posts, H' H², the former of which is electrically connected to 90 the post G, and the latter of which, H², is electrically connected to the lever E. Arranged below this pole-changer are two binding-screws—plus and minus—to which the cords connected with the electrodes J J, which 95 are to be used in contact with the patient, are connected. Also, mounted upon the frame or plate D is an interrupter, I, consisting of a vibrating reed, I', an electro-magnet, I², spring contact-finger I³, and circuit-terminals I⁴ and I⁵, and these are suitably connected in the circuit, as will be described hereinafter, and an interrupter-switch, I⁶, is arranged above the interrupter. Upon the upper part of this 100

plate or frame are arranged a series of switches, K, having suitable contact-points, by means of which the various resistance-coils R may be brought into or out of the circuit, and to the left of these switches is arranged a switch-arm, K', which is adapted to include the resistance-circuit. Below these switches is arranged another switching device, L, having several contact-points, by which the current produced may be rendered constant or interrupted, or may be made to pass through the resistance-coils and millampère-meter, and below this switch is another one, M, which controls the primary circuit of the induction-coil N. This induction-coil N is shown as mounted upon the base of the cabinet and to consist of two coils with a buzzer and contacts arranged, as is usual in such cases, and provided with a key, n, whereby the circuit of the secondary coil may be closed to act as a damper for the primary of the inductorium when the primary is used.

The binding-posts N' N² serve as connections for the electrodes of the secondary circuit, and the posts N³ and N⁴ serve as connections for the induction-coil.

N⁵ is a diagnosis-key for short-circuiting the primary of the induction-coil and enables the user to give single primary or secondary impulses.

Arranged in connection with the bracket or stand is a millampère-meter, and I have shown this as consisting of a box or case, O, provided with the usual adjusting devices and binding-screws, and having a mirror, P, arranged at an inclination to the face of the instrument, so as to reflect the condition of the needle or pointer and enable the operator to easily read the same. This mirror is fixed to a movable ring, O', so that it may be moved to any angle about the face of the instrument. This is suitably connected by the binding-posts o o to the main battery-circuits, and switches are provided, so that it may be included or excluded from the circuit as desired. In place of or in addition to the resistance-coils I use a water-rheostat, W, which is connected to the circuit 4 by the wire w and may be connected to the circuit 7 by the switch or connector X.

In order to make use of the devices thus far described, the circuits may be arranged as indicated in Fig. 2, and I will now trace the circuits, showing the application of the various currents to the patient and the way the apparatus described may be variously combined to produce different therapeutic effects.

As indicated, each of the pins F is connected to one of the opposite poles of each of two batteries, and the cord g is connected to the plug g', (shown in the present instance as fixed upon the pin No. 1,) and the other end of the cord is connected to the binding-post G. The swinging arm E is shown as resting on the pin 27, and the other end is connected to the pivot E', and it will thus be seen that

battery-cells from 1 to 27 are included between the binding-screw G and the pivot E'. It may be stated that the plug may be put upon any one of the cells desired and the handle moved upon any other, so that any one or all or any number of cells in series may be included between these terminals. From the terminal G the circuit 1 leads to the post H' of the pole-changer, and from the pivot E' the circuit 2 leads to the post H² of the pole-changer. The post H' is permanently connected to one side of the pole-changer, and the projections h² and h³ are also connected, and from h³ a circuit leads to the binding-post plus of the external circuit. The post H² is permanently connected to the other side of the pole-changer, and the pins or studs h h' are connected as shown, and from the stud h a circuit-wire, 3, leads to the switch L. From the minus binding-post a circuit, 4, leads to a contact-pin, 5, of the switch L and to another contact-point, 6, of the switch K', which switch is connected with the circuit 7 of the resistance R. This resistance is made up of a series of coils of various lengths and dimensions, and consequently of various resistances, and each of these is connected to a contact, 8, on one side and another contact, 9, on the other, which contact is connected to another contact-piece, 10, arranged adjacent to the contact-piece 8. Mounted on the contact 9 are levers or connectors K, which are arranged to bear upon either of the contacts 8 or 10 and to connect the corresponding contact, 9, therewith. It will be seen that when any particular lever is resting upon contact 10 the adjacent resistance-coil R is cut out of circuit; but when it is resting upon the adjacent contact, 8, the current passing through the connector K is forced to pass through the corresponding resistance, R, on its way to the next contact, 9.

It will thus be seen that as many or as few of the resistance-coils may be included in the circuit as desired. In the present instance the resistance-coil marked 1,000 and resistance-coil marked 20 are included in the circuit, while the others are cut out. These resistance-coils are shown arranged in two rows for convenience and compactness, and from the end of the lower row the conductor 11 extends to one of the binding-screws o of the millampère-meter O, and from the other binding-screw the conductor 12 leads to the contact-piece 13 of the connector L; also, from the minus binding-post extends a circuit, 14, which is connected to the vibrating arm I' of the interrupter, and from thence to the contact 15, from which a conductor, 16, leads to a contact-piece, 17, of the connector L, and thence when the connector is in proper position by conductor 3 to the pole-changer and to lever E. In order that the interrupter may be operated independent of the circuit including the patient, I connect it with the battery 26 of the induction-coil, and the conductors 27 and 23 lead therefrom to the ad-

- justing-screw I^4 , spring I^5 , and thence by circuit 18 around the coil of magnet I^2 to contact-point 19 of the switch I^6 , and thence by circuit 20 to the other side of battery 26.
- 5 The battery 26 is preferably arranged in multiple arc for quantity currents, and the conductor 27 branches at 25 and passes through the primary of the induction-coil N , and thence by wire 22 to a contact, 21, which may 10 be connected by switch M to the wire 20, and thence to the other side of the battery 26. A loop-circuit is taken from the opposite sides of the primary coil and connected to the binding-posts $N^3 N^4$, by which I am enabled to use 15 the interrupted primary circuit and get the benefit of the current due to the discharge of the core of the magnet.
- The secondary coil of the inductorium is connected to the posts $N' N^2$, and a switch, 20 n , is arranged to short-circuit or close the secondary circuit. A diagnosis-key, N^5 , is arranged between the conductors 20 and 22 to open and close the primary to produce single 25 impulses when the switch M is open.
- 25 Suppose now it is desired to apply a current from the twenty-seven battery-cells in circuit to a patient connected to the electrodes $J J$, and the operator wishes to know the relations of that circuit and the current 30 of that circuit to the resistance of the patient, (and we will suppose all the resistance-coils in the circuit to be cut out and the millampère-meter to be included,) the circuit may be traced as follows: from the binding-post G , 35 through the conductor 1, to the post H , and through the pole-changer to the plus binding-post, and thence through the electrodes to the patient and back to the minus binding-post. From thence it passes through the conductor 4 to the switch K' , and thence through 40 the connectors K and wire 11 to the millampère-meter O , and by the circuit 12 to the contact-piece 13, thence by the switch L and conductor 3 to the pole-changer, through 45 the contacts $h h'$ and post H^2 , and by way of conductor 2 to the pivot E' and lever E through the batteries to the binding-post G . The operator will then note the indication 50 on the millampère-meter and can tell 50 how much current is flowing through the body of the patient. In order to note the resistance of that body the circuit is traced as before to the plus binding-post, and from there by the conductor 28 it passes to the contact 55 29, and the lever K' is moved thereon, cutting out the patient, and thence the circuit passes through the lever K' and the resistance-coils to the millampère-meter and back as before to the other side of the battery, and the operator 60 will then cut in or out more or less of the resistance-coils until he gets an indication upon the millampère-meter the same as when the patient was included, and he is thus enabled to determine the resistance of the patient or the portion thereof which was before 65 included in the circuit with great exactness.

When it is desired to treat the patient to a

constant current of any particular strength, the number of cells desired are included between the points G and E , and the circuit may 70 be traced from G through the wire 1 to the pole-changer, to the plus binding-post, through the patient to the minus binding-post, and thence by the conductor 4 to the point 5, when, the conductor L being placed thereon, it passes 75 through the conductor 3 to the pole-changer and back to the pivot E' . By means of the pole-changer H the direction of this current may be varied according to the therapeutic effect desired, and, as before stated, the 80 strength is varied by including more or less of the cells in circuit.

When it is desired to treat the patient to an interrupted galvanic current, the circuit is traced as before to the plus binding-post, 85 through the patient to the minus binding-post, and thence through the conductor 14 to the vibrator I' of the interrupter, through the contact 15 and conductor 16 to the contact 17, thence through the connector L and circuit 3 90 to the pole-changer and back to the pivot E' , and the circuit is constantly opened and closed at the point 15.

In order that the connection of the interrupter may be constantly maintained, regardless of the strength of the current passing through the patient, I make use of the battery 26 for controlling its movements, as before stated, and the circuit may be traced from the said battery through the conductor 27 to conductor 23, thence to the adjusting-screw 14, through the contact-spring 15, the conductor 18, and magnet I^2 to the contact-point 19, and, the switch I^6 being closed on said point, thence by the conductor 20 to the other side of the battery 105 26. By this arrangement it will be seen that I have a constant battery force operating the interrupter, while the current passing through the patient may be varied from one extreme to the other without affecting the operation of 110 the interrupter, the speed of which may be adjusted as usual by any suitable means—as the adjusting-screw I^4 , which is a very important feature of my invention, especially in connection with the treatment of delicate patients. 115

When it is desired to make use of the secondary or faradic current, the patient is connected to the binding-screws $N' N^2$, and the primary circuit from battery 26 passes through the conductor 20 to the switch M , which is, in 120 this instance, first placed upon the contact 21 of the conductor 22, including the primary of the induction-coil N , and by conductor 27 to battery, and the usual interrupter of the induction-coil is used to make and break the 125 primary circuit.

In order to get the effect of a single impulse in one direction on the patient, the key N^5 may be operated to open or close the primary of the induction-coil.

In order to make use of the magnetic discharge or "extra current" due to demagnetizing a core of a magnet, the patient is connected to the binding-posts $N^3 N^4$, and the key N^5 is 130

operated to close and open the circuit including the battery and primary coil of the inductorium, and the extra current passes through the branch or loop circuit, including 5 the patient.

From the above it will be seen that all the various therapeutic effects may be produced by the various arrangements and connections, and that without delay or complicated arrangements or adjustments of the circuits and connections. It is evident that I am not limited to the precise arrangements and constructions shown, as they can be varied by those skilled in the art without departing 15 from the spirit of my invention.

What I claim is—

1. In a medical battery, the combination, with a series of cells, a pole-changer, and adjustable switches for including more or less 20 of cells in the circuit, of a pole-changer, electrodes for the patient, a series of resistances, a millampère - meter, and switches, whereby the resistance of the patient may be readily ascertained and the desired amount 25 and kind of current applied, substantially as described.

2. In a medical battery, the combination, with the electrodes, of an interrupter located in and breaking the circuit of the electrode 30 and an independent battery-circuit for operating the interrupter, substantially as described.

3. In a medical battery, the combination, with the primary circuit of the inductorium, 35 of a loop-circuit including electrodes connected therewith and a key in a short circuit

of the primary for opening and closing the same, substantially as described.

4. In a medical battery, the combination, with the primary of the inductorium, of a 40 loop-circuit including electrodes connected therewith and a key for opening and closing a short circuit of the primary, and a secondary circuit including electrodes and a key for opening and closing said secondary circuit, 45 substantially as described.

5. In a medical battery, the combination, with a base-piece containing switches and connections, substantially as described, of a millampère - meter connected thereto and provided with an inclined reflector, whereby the 50 indications of the current through said circuits and switches may be observed, substantially as described.

6. In a medical battery, the combination, with a base-piece, of a switch arranged to include more or less battery-cells in the circuit, a pole-changer, a millampère - meter, an interrupter, a series of resistance-coil switches, an induction-coil, a key for opening and closing the primary of said coil, and circuits and switches, substantially as described, all arranged on the base, whereby the different therapeutic effects may be produced in the manner set forth. 60

In testimony whereof I have signed my name to this specification in the presence of two subscribing witnesses.

HENRY E. WAITE.
